UNITED STATES PATENT OFFICE.

HERBERT FROOD, OF BUXTON, ENGLAND.

PROCESS OF MAKING BRAKE-BLOCKS.

1,096,705.

Specification of Letters Patent.

Patented May 12, 1914.

No Drawing.

Application filed September 4, 1913. Serial No. 788,458.

To all whom it may concern:

Be it known that I, HERBERT Frood, a subject of the King of Great Britain and Ireland, and a resident of Buxton, in the county of Derby, England, have invented certain new and useful Improvements in Processes of Making Brake-Blocks, of which the following is a specification.

With brake blocks, brake bands, flat or cone shaped friction clutch rings, or the like consisting of a thick woven fabric similar to driving belting and impregnated with cementitious material it is found that considerable and repeated adjustment is necessary for some time after the band, block, ring or the like is first put in place and put to work. I have found that the necessity for making such adjustment arises, not from the wearing away of the fabric, but from its diminution in thickness resulting from the working pressure put upon it, which diminution progressively continues, until the fabric has been reduced to the least thickness it is capable of being reduced to under such pressure. When this state is arrived at the fabric composing the band or the like is only further reduced in thickness as a result of the frictional wear and attrition to which it is subjected, and as the wear is very small very little adjustment is required after the fabric can no longer be reduced in thickness by the working pressure put upon it.

In carrying this invention into effect such a band, block, ring, or the like (all of which are included hereinafter in and by a reference to a brake block) has its woven fabric reduced to the required minimum thickness before it is put in use. This minimum thickness may vary according to the use to which the brake block is to be put, but it will be about or will be less than the thickness to which the woven fabric would be reduced under the pressure to which it would be exposed under its working conditions. The impregnated woven fabric which will ultimately be used as a brake block is subjected to sufficient pressure to properly reduce its thickness in a die, press, or the like which will reduce it to a thickness which can not be further reduced or materially further re-

duced solely by any working pressure to which it may be later subjected when it is in use. The pressure is preferably exerted while the brake block is in the form which it will occupy when in use. The block should be warmed to soften the hard cementitious material contained within it and the pressure be applied while the cementitious material is soft and comparatively non-resist- 55 ant. When the pressure is applied to the block in dies which are shaped to the form the block will have when it is in use, such dies inclose the block and prevent displacement or longitudinal extension of the fabric laterally or endwise while compression and reduction of thickness is taking place. Similarly other dies may also be shaped to restrain lateral and endwise displacement or extension of the fabric constituting the 60 block or the like during compression. 65 70

As an example of how much reduction in thickness may be accomplished according to this invention a piece of fabric woven solid to three-quarters of an inch in thickness 75 may be pressed between dies until it is only three-eighths of an inch thick. With blocks so compressed before they are put into use all the inconveniences of early considerable adjustments are avoided. 80

What I claim is:—

A process of forming a solid hard brake block from a thick woven fabric, which consists in impregnating the fabric with a cementitious substance which becomes hard 85 under ordinary temperature conditions, compressing the woven fabric while the cementitious substance is in softened condition to a materially less thickness than the ordinary thickness of the fabric, the compressing pressure being exerted normally to the face of the fabric which is adapted to become the braking surface and at the same time confining the fabric against spreading in any direction. 90 95

In witness whereof I have hereunto set my hand in the presence of two subscribing witnesses.

HERBERT FROOD.

Witnesses:

WILLIAM GEO. HEYS,
JOHN O'CONNELL.
